CLAIM

The ornamental design for a storage rack for attachment to the cab of a semi-trailer for holding a pair of safety struts, as shown.

DESCRIPTION

FIG. 1 is a perspective view of a storage rack for attachment to the cab of a semi-trailer for holding a pair of safety struts showing my new design;

FIG. 2 is a rear elevational view thereof;

FIG. 3 is a bottom plan view thereof;

FIG. 4 is a top plan view thereof; and

FIG. 5 is a right side elevational view thereof.
